COMBINED ROTARY TEST TUBE RACK AND INTERLOCKING BASE THEREFOR

Herman Barrantes and James Gilbert Thomas, Elkhart, Ind., assignors to Miles Laboratories, Inc., Elkhart, Ind., a corporation of Indiana

Filed July 23, 1965, Ser. No. 86,313

Term of patent 14 years

(Cl. D16—1)

FIGURE 1.

FIGURE 2.

FIGURE 3.

FIGURE 1 is a perspective view of a combined rotary test tube rack and interlocking base therefor embodying our new design;

FIGURE 2 is a side elevational view thereof; and

FIGURE 3 is a plan view thereof.

The broken lines are disclosed for illustrative purposes only.

We claim:

The ornamental design for a combined rotary test tube rack and interlocking base therefor, as shown and described.
